ILLUMINABLE SIGN

Hieme C. Hammer, 6N-130—Route 53, near Itasca, Ill.

Filed Nov. 8, 1961, Ser. No. 67,426

Term of patent 14 years

(Cl. D1—12)

FIGURE 1 is a perspective view of an illuminable sign showing my new design;

FIGURE 2 is a reduced top plan view thereof;

FIGURE 3 is a slightly reduced front elevation thereof;

FIGURE 4 is a side elevation thereof as shown in FIGURE 2; and

FIGURE 5 is a bottom plan view thereof as shown in FIGURE 2 the base being omitted for convenience of illustration;

FIGURE 6 is an enlarged fragmentary cross-sectional view of the spherical portion thereof.

It is to be understood that the fragmentarily shown protuberances on the inside of the spherical portion of

the sign are continuous throughout said spherical portion.

The dominant features of my design reside in the portions shown in full lines.

I claim:

The ornamental design for an illuminable sign, substantially as shown and described.
